UNITED STATES PATENT OFFICE.

MATTHÄUS LUTZ, OF STUTTGART, GERMANY.

PATTERN FOR DRAFTING GARMENTS.

SPECIFICATION forming part of Letters Patent No. 516,828, dated March 20, 1894.

Application filed September 19, 1893. Serial No. 485,839. (No model.)

To all whom it may concern:

Be it known that I, MATTHÄUS LUTZ, a resident of Stuttgart, Germany, have invented new and useful Improvements in Patterns for Drafting Garments, (for which I have obtained patent in no country,) of which the following is a specification.

The present invention relates to waist-patterns, and more especially to patterns adapted to fit waists to persons having various builds or—

The object of this invention is substantially to adapt one and the same pattern for fitting waists for all persons whose upper widths are equal, but whose shapes and carriage are different. This object I accomplish by making the pattern model of two pieces, instead of one, as heretofore, which pieces may be instantaneously adjusted for any attitude, or bend of the back.

In making garments, it is necessary, as is well-known, to prepare a so-called model from a flat pattern, which, after being united at the proper edges, will have a shape which will fit the body for which the garment is designed.

In this process, the forming of the model for the lower part of the garment (dress-waist) does not offer much difficulty, inasmuch as that part of the body which is to be covered thereby may be generally assumed to be in the form of the frustum of a cone, flaring from the waist portion to the arm-pits. The upper part of the garment (dress-waist), however, which may be regarded as a cone truncated obliquely, constitutes the part of the model, the fitting of which involves considerable difficulty. This obliquely-truncated cone, whose shape it is desired to retain with the greatest possible accuracy, rests upon the

lower frustum of a cone at its bottom and is bounded at its top by the neck opening. The relation between the rear and front vertical measurement of this obliquely-truncated cone, that is to say, between the back-measure and the front-measure, varies according to the attitude or carriage of the body. The base line of this truncated cone, moreover, is in the form of an irregular oval, whose form varies according to the curvature of the back.

In general, it may be assumed that the accurate fit of the garment, *i. e.*, the so-called balance of the entire cut, depends upon conform-

ing to the carriage of the body and the curvature or arching of the back, the sleeve-opening being also taken into account.

55

Notwithstanding the great number of garment-drafting systems in use, it has hitherto always been necessary for the same upper width of the body, to make a separate model for each separate carriage of the body and 60 curvature of the back, and this resulted in considerable loss of time and additional effort.

In the drawings accompanying this specification—Figure 1 represents a dress-pattern model embodying my invention, assembled; 65 and Fig. 2 represents the same separated into its parts.

As already stated, for the purpose of preparing the pattern-model, the upper body is assumed to be composed of two mathematical bodies, *viz*: the frustum of a cone, and a superimposed obliquely-truncated cone, both of these truncated cones having a common base, which lies in a horizontal plane passing through the arm-pits. If the frustum of a 70 cone is produced on the line of the backbone to the neck-opening measured in centimeters, this is termed the carriage or attitude of the body, *i. e.*, the smaller or greater this measure 75 is, the more or less erect is the carriage of the person measured, or, in other words, the more or less high breasted is the same. According as the carriage of the said person is more or less erect, the front line of the obliquely-truncated cone is longer or shorter. This 80 must be taken into account in the pattern-model, which, for this purpose, is made in two parts, at that point, instead of one, as formerly, the upper part, B, which has the 85 form of the obliquely-truncated cone developed into a plane, being pivoted at a point, *h*, lying upon a horizontal line, *Z—Z*, which forms a tangent to the arm-hole. This point, *h*, forms the intersection of the rear vertical line with the lower horizontal tangent to the arm-hole. The line, *Z—Z*, forms the line of 90 intersection between the developments of the obliquely-truncated cone and the frustum. 95

The part, C, of the pattern-model, forms 100 the development of the frustum into a plane, and is provided with a scale, *n*, formed on the arc of a circle from point, *h*, as a center, the said scale being provided with a slot, as

shown. The middle portion of this arc-shaped scale is located at the intersection of the arm-hole tangent, Z—Z, with an imaginary line drawn from the shoulder point, d' , to the front 5 waist point, d . For mean measurements, the distance from the pivotal point, h , to the scale n , exactly equals the distance of the former, (the point, h), to the neck-line, a , so that each centimeter of the carriage or attitude of the body, as measured, corresponds 10 exactly to a centimeter on the scale, n . Hence, if, for example, a measure of nine centimeters is taken for the carriage of the body, the part, Z, of the section, B, is moved to the 15 mark, 9, on the scale n , whereby the front part of the pattern-model is determined, all that is necessary being to now trace the outline of the two pattern-sections, B and C. For every normal attitude of the body, there 20 is a corresponding position of the arm-hole indicated on the pattern-model, and a scale m for this purpose is provided on the part, B, of the model. Assuming that an attitude of 10 has been measured, the part, B, is set to 25 the division-mark, 10, on the scale n of C, for the purpose of obtaining the correct outline. The division-mark, 10, of the scale m will then form the corresponding tangent for 30 the proper sleeve-opening. The rear portion of the pattern-model also depends essentially upon the curvature of the back. For normally built persons, it may be accepted as an empirical rule that the curvature of the back is equal to about one-half spinal curvature 35 (measured at the neck) less one centimeter. Large deviations occur here, flat backs being frequently coupled with great spinal curvature, and greatly-arched backs with an erect attitude or carriage. To compensate for these 40 variations, I provide the scale, o , located on the portion C concentric to point, h , and having graduations corresponding to the arching of the back, measured in centimeters. The 45 measurements required for this purpose, that is to say, to measure the deviations from the normal measurements, do not exceed eight centimeters, provided hump-backs are not considered, and, therefore, the scale, o , on the portion C is provided with graduations from 50 0 to 8, only. By means of this scale, o , the rear part of the pattern is fixed, i. e., the rear straight portion of B, is set to the proper graduation on the scale, o , after the front form of the pattern-model has been adjusted. The 55 curved line, b' , of the part, B, will then form the direction of the line, c , of part, C, that is to say, the continuation thereof. The back-portion, A, is not modified for any variation caused by different spinal curvatures or arch- 60 ing of the back, and is simply applied to the upper end of the edge, b' , beginning with its angle, a' .

The model is formed as follows: When the necessary measurements have been taken and 65 the common pattern-model for every upper width is provided, the part, B, is so set to the

part, C, that the former will indicate the carriage or attitude of the body on the scale, n , whereupon the front edge of the model is traced. The same graduation-mark on the 70 scale, m , to which the section, B, was set on the scale, n , is then selected, the said graduation mark being then produced to form the front tangent of the sleeve-opening. Finally, the section, B, is set with respect to the scale, 75 o , the line, b' , forming the direction for the line, c , of the part or section, C. The section, A, does not vary for the same upper width, and it is only to be observed that in sewing together the sections, it is attached in the correct position, as above stated. For one and the same upper width, or for only slightly varying upper widths of garments, the pattern-model may, therefore, be employed in connection with all spinal curvatures (bodily 80 attitudes), as well as all convexities or archings of the back. After all measures have been taken correctly, the pattern may be completed within two minutes at the utmost, inasmuch as it is only necessary to set the pivoted part on section, B, twice and then to 85 trace the outlines. The advantages of preparing a pattern in this way, especially for simple tailors who are not able to employ an extra-cutter, will be best apparent to those 90 skilled in the trade.

What I claim, and desire to secure by Letters Patent, is—

1. A pattern-model for drafting garments, consisting of two sections, B and C, the former being provided with an arm-eye opening, the sections being pivotally connected to each other, the pivotal point, h , of the same being the point of intersection of the lowermost horizontal and the rear vertical tangent to the 100 arm-eye opening, substantially as set forth.

2. A pattern-model for drafting garments, consisting of two sections, B and C, the former being provided with an arm-eye opening, the sections being pivotally connected to each 105 other, the pivotal point, h , of the same being the point of intersection of the lowermost horizontal and the rear vertical tangent to the arm-eye opening, the section, B, being provided with a scale, m , and the section, C, being provided with the scales, n and e , wherein by setting both sections with respect to the three said scales, m , n and o , the front pattern-outline, the front tangent to the arm-eye opening and the rear pattern-outline may 110 be determined, so that for equal or approximately equal upper widths of the body, the same pattern-model may be employed for variations in attitude and build, by proper adjustment.

In testimony whereof I have signed this specification in the presence of two subscribing witnesses.

MATTHÄUS LUTZ.
